UNITED STATES PATENT OFFICE.

EDWIN A. BLANCHARD, OF SAN DIEGO, CALIFORNIA.

PORTABLE IRONING-BOARD.

1,174,382.

Specification of Letters Patent.

Patented Mar. 7, 1916.

Application filed September 7, 1915. Serial No. 49,157.

To all whom it may concern:

Be it known that I, EDWIN A. BLANCHARD, a citizen of the United States, residing at San Diego, in the county of San Diego and State of California, have invented new and useful Improvements in Portable Ironing-Boards, of which the following is a specification.

The object of my invention is to produce an ironing board which combines simplicity, durability and rigidity of construction, and which may be readily attached to the back of a door or to the wall as desired; and my invention consists of the novel features herein shown, described and claimed.

An embodiment of my invention is shown in the accompanying drawings, in which—

Figure 1 is a perspective view showing my ironing board attached to the back of a closet door, the door being shown open with the ironing board and sleeve board in position for use. Fig. 2 is an edge view, as seen looking in the direction of the arrows 2 in Figs. 1 and 3, the board being shown in its folded position. Fig. 3 is an enlarged fragmentary front elevation, showing the ironing board and sleeve board as they appear when in position for use, as in Fig. 1. Fig. 4 is an enlarged vertical fragmentary detail, showing the mounting means for the supporting plate, and taken upon the line 4—4 of Fig. 3.

Referring more particularly to the drawings my invention consists of the supporting plate 1, which is preferably a board about 14" in width and of sufficient height to accommodate an ironing board 2. The ironing board 2 is hinged near the upper end of the supporting plate 1 by the hinges 3 and 4, and in such position that it may swing from a horizontal to a vertical position and be slightly shorter than the height of the door when in vertical position, so that the door may swing open or closed.

The ironing board brace 5 is hinged to the underside of the ironing board 2, about centrally thereof, by a pair of hinges 6 and 7, and extends backwardly and downwardly and engages in a notch 8 formed in the cleat 9, which is nailed across the lower end of the plate 1.

A sleeve board 10 is hinged to the upper end of the plate 1, by the hinges 11 and 12, just above the ironing board 2, and extends outwardly above said board and is

supported by a U shaped brace 13 provided with inwardly extending pintles. Eyes 14 and 15 are screwed into the underside of the sleeve board and the pintles of the U shaped brace 13 are inserted into the eyes 14 and 15, so that the brace may swing back and forth to support the sleeve board and fold against said board when out of use.

The supporting plate 1 is provided with elongated openings 16, 17, 18 and 19 for the reception of hooks 20, 21, 22 and 23. Said hooks are L screws inserted at an angle into the door 24, as shown in Fig. 4, so that when the plate 1 is inserted the hooks will extend through the openings 16, 17, 18 and 19 and jam against the outside of said plate to hold the plate and ironing board rigidly in place upon the door.

An eccentric block 25 is pivotally fastened by the screw 26 to the plate 1, under the inner end of the ironing board, and in such position that when the board is swung up, as in Fig. 2, said block may be turned to a vertical position to abut against the end of the board to hold the same in folded position.

The sleeve board 10 folds above the plate 1, against the door 24 and the ironing board 2 folds up against the sleeve board with the brace 5 against the back side thereof, so that the whole construction is very compact and convenient.

In the drawings I have shown the device mounted upon a door, which is the preferred form, but it is to be understood that it may be mounted in any convenient place upon the wall.

I claim:

A portable folding ironing board comprising a supporting plate, an ironing board proper hinged near the upper end of the supporting plate, means for supporting said ironing board in relation to said supporting plate when in open position, and an eccentric block pivotally mounted upon the supporting plate under the ironing board, so that when the ironing board is out of use it may be swung to vertical position and said eccentric block rotated to abut against the end of said board to hold the same in position against said supporting plate.

EDWIN A. BLANCHARD.
